UNITED STATES PATENT OFFICE

JOE PERKIN, OF BAYONNE, NEW JERSEY

DOORLOCK MARKER

Application filed November 11, 1927. Serial No. 232,588.

This invention relates to a door lock marker.

The invention is specially directed to a marker for mortise locks. The object of the invention is the production of a door lock marker, by means of which marks can be simultaneously indicated on a door to form the required openings and cavities for the attachment of a lock. The second object of the invention is the production of a door lock marker for a mortise lock, by means of which marks can be simultaneously indicated on a door and its accompanying jamb to form the required openings and cavities in both the door and jamb for the insertion of the lock in the door and the attachment of the striker plate to the jamb. The third object of the invention is the production of a door lock marker, by means of which both marks and cuts can be made in a door, so that the necessary holes and cavities can be made therein for the attachment of a mortise lock. The fourth object of the invention is the production of an adjustable door lock marker adaptable for locks that vary in size.

In the accompanying drawings Fig. 1 represents a side elevation of an exemplification of the improved door lock marker; Fig. 2 shows a bottom view of Fig. 1; Fig. 3 is a partial left hand side view of Fig. 1; Fig. 4 indicates a section of Fig. 3 on the line 4-4; Fig. 5 represents a right hand side view of Fig. 1; Fig. 6 represents a side elevation of another form of the door lock marker; Fig. 7 shows a bottom view of Fig. 6; Fig. 8 is a partial left hand side view of Fig. 6; Fig. 9 indicates an elevation of a cutting blade of the door lock marker; Fig. 10 is a top view of Fig. 9; Fig. 11 shows a section of Fig. 9 on the line 11-11; Fig. 12 shows a right hand side view of Fig. 6; Fig. 13 shows a section of Fig. 2 on the line 13-13; Fig. 14 indicates an elevation of the fragmentary portion of a door having a mortise lock inserted therein and a diagrammatic representation of some of the steps used with the marker; Fig. 15 shows a fragmentary elevation of the jamb of the door with its striking plate; Fig. 16 represents an end view of the door and a diagram of some of the steps

used with the marker and Fig. 17 indicates an end view of the jamb with its striking plate and a diagram of some of the steps used with the marker.

Referring to Figs. 1 to 5 inclusive and Fig. 13 the door lock marker is indicated with the elongated supporting block 20, having the front or bearing face 21, the rear face 22 and the side faces 23 and 24. In the side faces 23 and 24 are formed the similar dovetail guide grooves 25 and 26. Similar longitudinal cutting blades 28 are securely seated in the block 20 and project from its front face 21. Screws 29 are in threaded engagement with openings in said block and are positioned and adapted to bear against the rear faces of the cutting blades 28, to facilitate the removal of the latter from the said supporting block. A row of marking pins 30 extends from the face 21 of the block 20.

Two pairs of similar adjustable arms 32, having the opposite faces 33 and 34 are adjustably connected to the side faces 23 and 24 of the block 20. At one end of each of the arms 32 is formed a head 38. The latter has extending from its opposite faces dove tail projections 39 and 40. Scales 41 and 42 are indicated on the face 23 of the block 20, each of which coacts with one of the faces of the heads 38.

It will be noted that one of the faces of the head 38 is in line with the face 33 of the arm 32 and that the other face of the head 38 is spaced from the plane of the face 34. The dove tail projections 39 and 40 are adapted to engage the dovetail guide grooves 25 and 26. Referring to Fig. 2 it will be noted that the projections 39 engage the grooves 25 and 26 which locates the faces 33 of the arms 32 in line with the side faces of the supporting block 20. A screw 45 is in threaded engagement with an opening in each of the heads 38. The screw 45 is adapted to bear against the bottom face of each of the grooves 25 and 26 and thereby force the dovetail projections 39 and 40 against the inclined faces of the guide grooves 25 and 26. A jam nut 46 is provided for each of the screws 45. The location of the arms 32 as plainly indicated in Fig. 2 have their inner faces 33 spaced to be

suitable for a door $1\frac{3}{8}$ inches thick. When the arms 32 are reversed in position and locked in place, the faces 34 of the arms 32 will be opposite each other and spaced apart to be suitable for a door $1\frac{3}{4}$ inches thick.

Two of the adjustable arms 32, have each detachably clamped thereto a marking arm 48, by means of a bolt 49, which engages a threaded opening in its accompanying arm 32. A wing nut 50 engages the bolt 49 extending from the arm 32 and a washer 51 is interposed between the nut 50 and the arm 48. An elongated opening 53 is formed in one end of each of the marking arms 48 and a guide opening 54 is formed in its other end. A projection 55 extends from one end of each of the marking arms 48, and which coacts with a scale 56 indicated on each of the adjusting arms 32. A spring 62 is provided for each of the marking arms 48 and has one end fastened thereto. From the other end of each of said springs 62 projects a marking pin 63, the tip end 64 of which is normally spaced from the plane of the adjacent side face of the supporting block 20. The pin 63 extends through the guide opening 54 adjacent thereto.

To the middle portion of the block 20 is fastened the bifurcated journal bracket 68. A main operating handle 70 is shown having the handle portion 71 at one end, indicated as broken away, and is pivoted to the journal bracket 68 by means of the screw pivot 69, and has the flange 72 at the other end. The flange 72 has formed therein the dovetail guide groove 73. A block 74 has formed therewith the dovetail projection 75, which is guided in the guide groove 73. In the upper face of the block 74 is formed a dovetail guide groove 79. In the latter are seated the adjustable plates 80 and 81 which have respectively extending therefrom the marking pins 82 and 83. The plates 80 and 81 have each extending therefrom the apron 84. A pair of similar screws 85 and 86 are in threaded engagement with openings in the block 74. Each of said screws 85 and 86 has a shank 87 journaled in one of the aprons 84, and each of said screws 85 and 86 are respectively provided with an operating knob 88. A bolt 94 has one end tightly secured to the block 74 and extends through the guide opening 95 in the flange 72. By means of the nut 96 the block 74 can be clamped to the flange 72 in different positions to be suitable for jambs of different thicknesses. A pair of scales 97 and 98 may be indicated on the block 74 which respectively coact with the pointers 99 and 100 on the plates 80 and 81. From the handle 70 extends the arm 101, which has pivoted thereto the journal brackets 102, by means of the screw pivot 103. A pusher plate 104 is fastened to the brackets 102.

In the rear face 22 of the block 20 is formed

a longitudinal dovetail guide groove 105. A pair of similar adjustable plates 106 and 107 are seated in the guide groove 105. Each of the plates 106 and 107 has extending therefrom the post 110. A blade operating handle 111 is pivoted to each of the posts 110, by means of the screw pivot 112. Washers 113 and 114 are provided for each screw pivot 112. To each handle 111 is fastened the cutting blade 115. For each of the adjustable plates 106 and 107 is provided a screw 118, which is in threaded engagement with said plates 106 and 107, while the ends of said screws are adapted to bear against the block 20. A jam nut 119 is provided for each of the screws 118. A pair of scales 125 and 126 are indicated on the face 22 of the block 20, and pointers 127 and 128 coact with said scales are indicated on the plates 106 and 107.

Referring to Figs. 6 to 12 inclusive, another form of the improved door lock marker is shown. In this form the supporting block is indicated at 20, with its front or bearing face 21, rear face 22 and the side faces 23 and 24 having the guide grooves 25 and 26. The longitudinal cutting blades 28 are again indicated with their screws 29. Marking pins 30 again extend from the face 21 of the block 20. The adjustable arms are again shown at 32 with their faces 33 and 34 and their heads 38 with their appurtenances. Scales 41 and 42 are again indicated on the face 23 of the block 20. The screws for the heads 38 are again indicated at 45.

To the middle portion of the block 20 is again fastened the bifurcated journal bracket 68. The main operating handle 70 is again shown with its handle portion 71 and the flange 72 and is pivoted to the bracket 68, by the same pivot 69. A block 74 is again adjustably connected to the flange 72 as described. The block 74 is again provided with the adjustable plates 80 and 81 with their marking pins 82 and 83. The screw 94 again clamps the block 74 in different positions. The scales 97 and 98 are indicated on the block 74 and coact with the pointers 99 and 100 on the plates 80 and 81.

From the operating handle 70 extends the arm 135, which has adjustably supported thereon the housing 136. A scale 137 is indicated on the arm 135 which coacts with one of the end faces of the housing 136. A screw 138 engages a threaded opening in the said housing 136 and is adapted to bear on the arm 135 to clamp the said housing to said arm. A jam nut 138^a is provided for the screw 138. Cross bars 139 and 140 extend from opposite sides of the housing 136. A housing 145 is adjustably supported and clamped to the bar 140, by means of the screw 146 with its jam nut. A boss 147 extends from the housing 145 and has secured thereto one end of a spring. The said spring comprises the central member 148 and the end

members 149 and 150. The member 149 is fastened to the boss 147, by means of the screw 151. The member 150 of the spring has extending therefrom the marking pin 152, which is normally spaced above the face 33 of the adjustable arm 32. A housing 155 is supported and clamped to the bar 139, by means of a screw 156 similar to 146, and a spring having the end member 149 and other appurtenances as already described is fastened to the housing 155 by means of the screw 151. A marking pin 152 on the latter spring is also normally spaced from the face 33 of its adjacent adjusting arm 32. It will be noted that the housing 136 is located midway between the ends of the bars 139 and 140. Scales 157 and 158 are formed on the bars 139 and 140 which respectively coat with the adjacent edges of the housings 155 and 20 145. In the rear face 22 of the block 20 is again formed a longitudinal dovetail guide groove 105. The adjustable plates 106 and 107 are again seated in the groove 105 and are provided with the pointers 127 and 128 which coat with the scales 125 and 126 on the block 20. Each of the plates 106 and 107 has extending therefrom the housing 108 having the dovetail guide 109. A post 110 extends from each housing 108. An operating handle 160 with the hub 161 is pivoted to each of the posts 110, by means of the screw pivot 162. From each of the hubs 161 extends an arm 163 which terminates in the rounded end 164. Cutting blades are designated in their entireties by the numeral 170. Each cutting blade comprises the rectangular body portion 171, from which extends the cutting member 172. From the outer face of the body portion 171 extends the dovetail guide bar 173. A plate 174 extends from the guide bar 173 and from the latter extend the stops 175. The cutting blades 170 are seated in the housings 108 engaging the guide 173 with the groove 109. The rounded end 164 of each operating handle 160 is then located between the stops 175.

Referring to Figs. 14 to 17 inclusive, a fragmentary portion of a door is indicated at 180 with a mortise lock inserted in the usual opening made in said door. The lock is indicated with the body portion 181 having the front end 182.

The bolt of the lock is shown at 183 and its latch at 184. The key hole of the lock is indicated at 185 and the supporting bar for the knob is shown at 186.

A circular opening 187 is made through the door 180 for the bar 186 and its knob not shown. The numeral 188 indicates a mark to locate the opening 187 in the wall of the door and which is impressed therein by the door lock marker as will be described. A circular opening 190 is made in the door for the key hole and 191 indicates a mark in the wall of the door which is impressed therein

by the door lock marker to locate the opening 190. The striking plate for the lock is indicated at 195 with its usual openings 196 and 197.

The numerals 198, 199, 200 and 201 show marks made in the jamb 202 for the striking plate by the door lock marker. In Fig. 16 are shown recesses 205, 206 for the plate 182, which are made in proper position by the marks or cuts 207, 208, 209 and 210 produced by the marking tool. The numerals 215 show marks made in the end of the door by the marking tool for the insertion of the bit to drill the openings indicated at 216 in the door for the body of the lock.

To use the door lock marker and referring to Figs. 1 to 5, 13 and Figs. 14 to 17, the operator engages the swinging end of the door 180 by the adjusting arms 32 at the required distance from either the top or bottom of the door. The faces 33 of said arms 32 being spaced from each other a slightly greater distance than the thickness of the door 180. The block 74 is located with its marking pins 82 and 83 in the longitudinal center line of the jamb 202 of the door. The operator then forces the handle portion 71 in the direction of the arrow A (Fig. 2) and the marks 188 and 191 are made in one of the faces of the door by the tip ends 64 of a pair of the marking pins. The cutting blades 28 insert the cuts 207 and 208 in the end of the door, and the pins 30 insert the marks 215 in said end. At the same time the pins 82 and 83 insert the marks 199, 198, 200 and 201 in the jamb of the door. The operator while holding the door lock marker as positioned, swings the blade operating handles 111 and thereby the cutting blades 115 insert the cuts 209 and 210 in the end of the door. The operator now releases the door lock marker, and the holes 187, 190 and 216 can be easily drilled in proper position. The recesses 205 and 206 can be easily made with a chisel.

The striking plate 195 is now located with its longitudinal center coincident with the marks 198, 199, 200 and 201 and the outline of the openings required therefore in the jamb can be easily made by scribing the contour of all parts of the striking plate 195 on the end face of the jamb.

It will be noted that the heads 38 with their appurtenances can be clamped different distances apart in the direction of the longitudinal axis of the block 20, and their positions noted by the scales 41 and 42, and also that the marking arms 48 can be clamped in different positions along their longitudinal axis and their positions noted by the scales 56. Therefore the positions of the marking pins can be varied to suit different locks, and which positions are determined before the marking pins 63 function. The adjustable plates 106 and 107 can be clamped in different

positions to the block 20, by means of the screws 118 and their positions noted by the scales 125 and 126, whereby the cutting blades 115 can be spaced different distances apart 5 for locks with different lengths of plates 182. The adjustable plates 80 and 81 can be moved different distances apart by means of the screws 85 and 86, and thereby each pair of marking pins 82 and 83 can be located in different positions in the direction of the longitudinal axis of the block 72. The block 74 can be clamped in different positions, by means of the screws 94 and thereby the line running through the pins 82 and 83 can be 10 located different distances from the face 72a of the operating handle 70 to suit different thickness of jambs.

The operation of the second door lock marker indicated in Figs. 6 to 12, is essentially the same as that described for Figs. 1 to 5, 13 and Figs. 14 to 17. I wish to state that the cutting blade 115 indicated best in Fig. 2 swings in the arc of a circle, while the cutting member 170 (see Fig. 6) reciprocates in a 15 straight line. Referring to Fig. 7, when the handle portion 71 swings in the direction of the arrow A', the marking pins 152 swing in the arc of a circle but as soon as the tip ends of the pins 152 pinch the side walls of the door 180, the flexibility of the springs having the members 148, will permit the said marking pins 152 to enter the doors in lines perpendicular to their side faces.

It will be noted that the adjustable arms 32, 20 (Figs. 2 and 7) with their appurtenances and the operating handle 70 with its appurtenances can be reversed in position relatively to the block 20, so that the marker may be adapted for right and left hand doors.

The operating handle 70, may be considered a presser bar, with which the marks 188, and 191 for the side face of the door, the marks 215 for the end of the door, the cuts 207 and 208 for the end of the door, and the marks 198, 210 and 201 in the jamb of the door may be 25 simultaneously made. Various modifications may be made in the invention and the present exemplification is to be taken as illustrative and not limitative thereof.

Having described my invention what I desire to secure by Letters Patent and claim is:

1. In a door lock marker the combination of an elongated supporting block having a bearing face and side faces at right angles to said bearing face, cutting blades disposed longitudinally of said block and from the bearing face of the block, marking pins extending from the bearing face of the block, 30 arms adjustably connected to the side faces of the block, a journal bracket extending from the face of the block opposite its bearing face, a main operating handle pivoted to the journal bracket, said operating handle having a handle portion at one end and a flange

at the other end, a block supported on the flange, marking means supported on the latter block, an arm having one end fastened to the operating handle, marking means carried by the arm, posts extending from the ends of the block and an operating handle pivoted to each post, a cutting blade extending from each of the latter operating handles, the cutting blades and marking pins extending from the bearing face of the supporting block being simultaneously pressable into a side face and the end of a door with the swinging of the main operating handle toward the end of the door and the block of said flange bearing against the jamb of the door.

2. In a door lock marker the combination of an elongated supporting block having a bearing face and side faces at right angles to said bearing face, said block having dovetail grooves in each of its side faces, cutting blades disposed longitudinally of the block and extending from its bearing face, marking pins extending from said bearing face of the block, arms each having a head, dovetail projections extending from the opposite faces of said heads adapted to engage the grooves in the side faces of the block, a journal bearing extending from the face of the block opposite its bearing face, a main operating handle having a handle portion at one end and a flange at its other end, a second block supported on said flange, an arm having one end fastened to said main operating handle, marking means carried by the arm, adjustable plates supported lengthwise of the supporting block, a post extending from one of the ends of each of said plates, an operating handle pivoted in each post, a cutting blade extending from each of the latter operating handles, plates slidably supported in said second block, and marking pins extending from the latter plates, the marking means of the arm and the cutting blades of the supporting block respectively being pressible into a side face and edge of a door and the marking pins of the plates of the second block at the same time being pressible into the jamb of the door.

3. In a door lock marker the combination of an elongated supporting block having a bearing face and side faces at right angles to said bearing face, cutting blades longitudinally disposed thereof, marking pins extending from the bearing face of the block, arms adjustably connected to the sides of the block, a journal bracket extending from the face of the block opposite its bearing face, a main operating handle pivoted to said journal bracket, an arm having one end fastened to the said main operating handle, a housing adjustably supported on said arm, cross bars extending from the opposite faces of said housing, a housing adjustably supported on each cross bar, a spring extending from each

of the latter housings and a marking pin extending from each spring.

4. In a door lock marker the combination of an elongated supporting block having a bearing face and side faces at right angles to said bearing face, arms adjustably connected to the side faces of the block, plates slidably supported in the face of the block opposite its bearing face, a housing extending from each of said plates, a post extending from each housing, a cutting blade slidably supported in each of said housings and an operating handle pivoted to each post and connected to its adjacent cutting blade.

15. 5. In a door lock marker the combination of an elongated supporting block, a journal bracket extending from the supporting block, a main operating handle pivoted to the journal bracket, a flange having a guide groove and an elongated opening at one end of the handle, a second block having a projection and a groove, said projection engaging the guide groove in said flange, a bolt extending from said projection through said elongated opening in said flange to clamp said block in different positions, a pair of adjustable plates slidably supported in the groove in said second block, marking pins extending from said plates, an apron extending from the outer end of each adjustable plate, a screw for each apron having a shank journaled in the apron and an operating knob at one end of each screw, each of said screws being in threaded engagement with a threaded opening in said block.

6. In a door lock marker the combination of a supporting block having a bearing face adapted to bear against the end face of the swinging end of a door, arms each having a head adjustably connected to the opposite side faces of said block, said side faces being at right angles to said bearing face and having a pair of scales marked thereon coacting with said heads to locate them in proper position, a journal bracket extending from the face of the block opposite its bearing face, a main operating handle pivoted in said journal bracket, an arm extending from said handle, a housing adjustably supported on the arm, said arm having a scale marked thereon coacting with said housing, cross bars extending from the opposite ends of the housing, a housing adjustably supported on each cross bar and a scale marked on each cross bar coacting with the housing adjustably supported thereon.

7. In a door lock marker the combination of a supporting block having a bearing face adapted to bear against the edge of a door and having side faces at right angles to said bearing face, arms adjustably connected to the side faces of said block, adjustable plates slidably supported in the face of the block opposite to its bearing face, a housing ex-

tending from each adjustable plate, a cutting blade slidably supported in each housing, a post extending from each adjustable plate, an operating handle pivoted to each post and connected to its adjacent cutting blade, a pair of scales indicated on the face of the supporting block opposite its bearing face and a pointer marked on each adjustable plate, each coacting with one of said scales.

8. In a door lock marker the combination of an elongated supporting block having a bearing face adapted to bear against the end face of the swinging end of a door, said block having side faces at right angles to said bearing face, adjustable arms extending from the side faces of the block to maintain it in operative position by bearing on the opposite faces of the door operated upon, a journal bracket extending from the face of the block opposite its bearing face, a main operating handle pivoted to said journal bracket, an arm extending from said handle and marking means supported on said arm.

9. In a door lock marker the combination of a supporting block having a bearing face, means extending from the block to maintain it in operative position on a door with its bearing face bearing on the edge face of the swinging end of the door operated upon, a journal bracket extending from the face of the block opposite its bearing face, a main operating handle pivoted to said journal bracket and marking means supported on said handle, said marking means being adapted to impress marks on the jam of the door upon the swinging of said handle.

10. In a door lock marker the combination of a supporting block having a bearing face adapted to bear on the edge face of the swinging end of a door, means extending from the block to maintain its bearing face in operative position, a journal bracket extending from the face of the block opposite its bearing face, an operating handle pivoted to said journal bracket, means extending from said handle to impress marks on a side face of the door and other means carried by the operating handle to impress marks on the jamb of the door, all of said marks being made upon the swinging of said handle.

11. In a door lock marker the combination of an elongated supporting block having a bearing face adapted to bear against the edge of the swinging end of a door, cutting blades disposed longitudinally thereof and extending from said bearing face of the block, said block having side faces at right angles to said bearing face, adjustable arms extending from said side faces to maintain the block in proper operative position, by bearing on the opposite faces of the door operated upon, a journal bracket extending from the face of the block opposite its bearing face, an operating handle pivoted to said journal bracket, an

arm extending from said handle and marking means connected to the latter arm, said cutting blades being pressable into the edge of the door and the marking means being pressable into a side face of the door upon the 5 swinging of said handle.

In testimony whereof I affix my signature.
JOE PERKIN.
